UNITED STATES PATENT OFFICE.

HENRY F. NEWBURY, OF BROOKLYN, NEW YORK.

TIME-LOCK.

SPECIFICATION forming part of Letters Patent No. 297,623, dated April 29, 1884.

Application filed January 24, 1883. Renewed March 27, 1884. (No model.)

To all whom it may concern.

Be it known that I, HENRY F. NEWBURY, of Brooklyn, in the county of Kings and State of New York, have invented certain new and useful Improvements in Chronometric or Time Locks, (Case U;) and I hereby declare that the following is a full, clear, and exact description of my invention, and will enable others skilled in the art to which it appertains to make and use the same.

A chronometric or "time" lock, as the term is understood in the art of safe and vault protection, is a lock or bolt whose checking device (sometimes technically called "dog") is for the purpose of unlocking, at least under the control of a time-movement capable of withdrawing it automatically, or of permitting it to be withdrawn, from the locking position upon the arrival of the hour for which the mechanism has previously been set. One construction of time-lock is illustrated and described in Letters Patent of the United States No. 213,809, granted to Charles E. Chinnock April 1, 1879; and the present invention relates particularly to the mechanism shown and described therein, the object being to render the same more efficient and secure. One of the principal features of the Chinnock lock is the employment of an electromotor to retract the bolt of the lock in the event of the clock (or clocks, if more than one be used) being stopped. Without the use of some mechanism having this capacity, the simple stopping of the clock before the arrival of the predetermined hour for unlocking would produce a "lock-out," since the dial through which the mainspring is enabled to act upon the lock-bolt would come to a halt when the mainspring ceases to uncoil. The occurrence of a lock-out would necessitate the forcing of the door of the safe or other structure guarded, and this not only would be expensive, but would render the safe or vault useless for an inconvenient period of time. As a protection against the evil attending the possible failure of the clock or clocks to operate, Chinnock placed a small electromotor in the lock-case, constructed to be operated with a slow and regular motion by electrical connection with a battery or other generator of electricity outside of the safe, and so arranged that when thus operated it would

maintain the dial in revolution, even though the mainspring should cease to act. This was done by utilizing the motion of the armatures of the electro-magnets to operate a train of 55 gears connecting with the dial-arbor. The dial itself was supported on a sleeve on this arbor, such sleeve being also provided with a gear-wheel for connecting with the mainspring-arbor. Under normal conditions the main-spring, acting through this gear, would cause the sleeve and dial to revolve around the dial-arbor, the latter remaining stationary; but if the latter were rotated by the electromotor, a pawl-and-ratchet connection between the dial 60 and the arbor would compel the two to move in unison.

The construction of Chinnock's electromotor and its connection with the dial are illustrated in the accompanying drawings, in 70 which—

Figure 1 represents a Chinnock lock (embracing the modifications which constitute the present invention) applied to the inner face of the door of a safe, Fig. 2 being a vertical 75 transverse section of the lock on the line *x x*, showing certain parts of the mechanism on the left of said line, and Fig. 3 being a similar section on the line *y y*, looking toward the right. Fig. 4 is a front view of a portion of the mechanism, showing the dial, the unlocking-lever, and certain connected devices, while Fig. 5 is a plan of a portion of the mechanism shown in Fig. 4.

Referring to these drawings more in detail, 85 A is the lock; B, one of the plates forming the frame of the time-movement, (or movements;) C, the lock-bolt; D, the dial; E, the safe-door; F, the frame or jambs thereof; G G, the door-bolts; H, the carrying or tie bar; I, one of the 90 bolt-bars; J, an abutment or bearing for the end of the bolt C; K, an elbow or bell-crank lever connected by the link L with the tie-bar H. When the lock bolt or dog is interposed between the abutment J and the head of the 95 angle-lever K, the door-bolts are locked. When the lock-bolt is retracted, the door-bolts can be thrown back and the door opened. The retraction of the lock-bolt is effected by means of the bent lever M M'. The lower arm, 100 M, of this lever, or rather the supplemental lever N, attached to this lower arm, is interposed in

the path of the unlocking-pin *d*, projecting from the rear face of the dial. The advance of this pin depresses the lower end of the unlocking-lever, and this in turn draws back the lock-bolt in opposition to the resistance of the spring *O*. The dial, it will be observed, is mounted on a sleeve, which also carries a gear-wheel, *P*, Fig. 2, which wheel is driven by a train of wheels (not shown in the drawings) connecting it with the mainspring-arbor *Q*. The mainspring is in the drum *Q'*. By properly seating the pin *d* on the dial, this mechanism, barring accidents, can be made to retract the lock-bolt, and thus unlock the safe at any required hour.

The clock-work which regulates the speed of the mainspring is not shown in the drawings, as it forms no part of the present invention, and may be of any suitable construction.

As hereinbefore indicated, if by any accident the clock stops, so that the mainspring ceases to act on the dial, the dial can be actuated by the electromotor through suitable electrical connections with the exterior of the safe.

R R' represent, respectively, the magnets and the armatures of this motor. Each time the magnets are energized the armatures are attracted and raised as rapidly as the pendulum-governor *R²* will permit, and this movement of the armatures is utilized, by means of gravity-pawls *r* and retaining-pawls *r'*, to advance the ratchet-wheels *S* upon the worm-shaft *s*. The rotation of this shaft revolves the worm-wheel *T*, and thence motion is communicated, through the train of wheels and pinions *T', T², T³, T⁴, T⁵, T⁶*, and *T⁷*, to the dial-arbor *U*.

Between the dial-arbor and the sleeve upon which the dial is immediately mounted, there is a pawl-and-ratchet connection, *U'*, so that the rotation of the dial-arbor, when driven by the electromotor, will cause the dial to revolve.

The construction of the governor, as well as of the train intermediate between the motor and the dial-arbor, is such that the dial can be operated by this means with a slow motion only. Consequently there exists no danger of this method being available to open the safe surreptitiously.

From the foregoing description of Chinnoch's motor, it will be readily be understood that it was designed to guard against that class of accidents only which merely cause the clock of the time-lock to stop without running down. If, on the other hand, the lock by any means should be so injured as to free the mainspring from the control of the escapement, the clock would run down with a highly accelerated speed, and almost instantly draw back the lock-bolt. Manifestly, under such circumstances, the electromotor would be of no value. I have discovered that one way in which this premature retraction of the bolt can be effected is by the explosion of a small charge of dynamite or other quick explosive against the exterior of that part of the safe to the inner

face of which the lock is attached. Assuming the lock to be mounted in such a way as to receive a severe blow from the inward movement of the door or wall of the safe under the force of the explosion, (which would inevitably be the case with the ordinary modes of mounting, as heretofore practiced,) the more delicate parts of the clock-work are liable to

be broken by the shock. When this occurs, the mainspring runs down at once, and the lock-bolt thereupon is retracted. To guard against this result under such circumstances, I have heretofore devised various modes of

construction, whereby the shock which breaks the clock mechanism may be caused to interrupt the connection between the mainspring and the dial, or between the dial and the lock-bolt.

One mode of doing this is described in Letters Patent of the United States No. 262,094, granted me August 1, 1882; and it consists in

mounting the dial loosely on its shaft, so that it may be thrown forward by the shock sufficiently to carry the unlocking-pin *d* beyond the range of the unlocking-levers *M N*; or in

so mounting the pin *d* in the dial that it will be dislodged by the shock, and thus permit the dial to revolve freely without affecting the unlocking-levers.

Another mode, as illustrated in said patent, consists in so constructing the unlocking-lever intermediate between the dial and the lock-bolt that it or a portion thereof will be carried by the force of the shock out of range of the unlocking-pin on the dial.

With these constructions the mainspring may run down without retracting the lock-bolt, and for this reason they constitute valuable improvements in the art; but as the result is accomplished by interrupting the operative connection between the dial and the lock-bolt, it is manifest that Chinnoch's supplemental unlocking mechanism would be of no avail to prevent a lock-out.

So, also, when these parts are made movable for the purpose indicated, there is a liability that they may accidentally become displaced by careless manipulation, in which case the Chinnoch mechanism would be insufficient to prevent a lock-out.

To obviate this difficulty, under these or any similar circumstances, I have devised a mode of causing the electromotor to operate upon the lock-bolt independently of the dial.

This I effect by means of the pinion *V*, keyed upon the dial-arbor, the spur-wheel *V'*, driven thereby, and the hooked link *V²*, one end of which is pivoted to the arm *M'* of the unlocking-lever, and the other or hooked end of which is arranged to engage, at the proper time, with a pin, *t*, projecting from the side of the wheel *V'*.

As the dial-arbor slowly rotates under the successive impulses imparted by the vibrations of the armatures, the wheel *V'* revolves until the pin *t* is brought into engagement with the link *V²*, when the further revolution of the wheel draws back the lever *M'*, and thus retracts the dog or lock-bolt from the locking position.

When this new connection between the electromotor and the lock-bolt is established, the electromotor will draw the dial-arbor around, and the dial will revolve, carrying the pin *d* with it, so that it will always be in proper position to draw back the lock-bolt.

bolt is used, it does not become necessary to discontinue the use of the old one. The latter will still be available under the circumstances for which it was originally designed—that is, 5 when the clock simply stops without other derangement. Under such circumstances the safe could be unlocked by the use of the electromotor in what was left of the time for which the dial was originally set. When, 10 however, the unlocking is done through the new connection, it must be effected in a stated time, as determined before the safe is locked. When the new connection is used, it is deemed prudent to make the wheel V' of larger diameter than the pinion V . This would correspondingly increase the time necessary to effect the unlocking of the safe in this way, and thus would diminish the chances of its being done surreptitiously. It will be manifest, also, 15 that the new connection between the motor and the unlocking-lever, independent of the dial, may be made in various ways otherwise than by a pinion, V , on the dial-arbor. The dial-arbor will be found a convenient support 20 for the pinion; but it may be mounted on a shaft of its own.

In order to arrest the action of the motor when the lock-bolt has been fully retracted, I so arrange the electrical connections that the 30 bar portion of the lock-bolt acts at the proper time as a cut-out, to short-circuit the magnets of the motor. Normally, the current entering the lock at the insulated post W passes along the insulated conductor W' to the second post, 35 W'' , thence to the magnets, and from the latter to the lock-case. An insulated stud, w , connecting with conductor W' , projects into the path of the lock-bolt, which, however, is partially cut away at this point, as shown in Fig. 40 1. When the bolt is in the locking position, it does not touch this stud. When, however, the bolt is drawn back, contact is effected, and this transfers the current directly from the conductor W' to the walls of the lock, and thence to the safe. This will prevent the 45 motor from continuing its action after the bolt is fully retracted. Without some such device the parts would be in danger of becoming strained and broken.

50 In order to detect any tampering with the supplemental unlocking mechanism, by way of working the electromotor surreptitiously, an indicator, X , may be used. The indicator may be operated by any suitable connection with 55 or from the dial-arbor, or from any other part whose motion is derived from the electromotor.

In the Chinnock lock, patented as above stated, the unlocking-pin d was not made to 60 act directly upon the bent lever $M M'$, but through a forked secondary lever, N . The object of such secondary lever was to provide a means whereby, when required, the time mechanism could run for a longer period than twenty-four hours without unlocking the safe. By 65 this means the lock could be made to furnish protection on Sundays and other holidays, as

well as for a single night. By the modifications which I have made in the construction and the adjustment of the secondary lever, I 70 have not only provided for securing protection when two holidays occur consecutively, but I also have guarded against the danger of the unlocking-pin striking against the end or point of one of the prongs of the secondary 75 lever, and thus arresting the movement of the clock or clocks and producing a lock-out. The construction and arrangement of this lever N and the associated parts is fully shown in Figs. 3 and 4. The lever is pivoted at a to the lower 80 arm, M , of the main unlocking-lever, and its range of movement on its pivot is limited by the length of the curved slot a' . Spring-pins $b b'$, acting against the studs $c c' c'' c'''$, hold the lever N in any required position relatively to 85 pin d . When, for instance, the lever N is adjusted, as shown in Fig. 4, the first revolution of the dial will bring the pin d in contact with the prong n' and immediately cause the lever $M M'$ and the lock-bolt C to partake 90 of the motion imparted to said secondary lever. If, however, the lever N be so adjusted that the pin b rests against the under inclined face of the stud c' , the prong n'' will be brought into the path of the dial-pin d , and the first 95 revolution of this pin will simply move the lever on its pivot without affecting the main lever $M M'$, but will bring the prong n' into the path of the pin d , so that on its next revolution the safe will be unlocked. In like manner, if 100 the lever N be so adjusted that the pin b' comes below the stud c'' , the prong n' will be brought into the operative position for unlocking by two successive movements of the lever on its pivot, effected by two successive revolutions 105 of the dial. This last adjustment is to be used when it is desired to have the safe remain locked for two days and three nights.

It will be observed that the studs $c c'$, &c., are made square on the top, but inclined on 110 the under side. By making them square on the upper side, they serve as positive stops to prevent the accidental movement of the secondary lever when one is adjusting the dial. By making them inclined on the under side, 115 the pins b and b' (which are to be held in their advanced position by small spiral springs) are caused to yield when the pin d presses on the prongs of the lever N . The springs which control the pins $b b'$ must, of course, be weaker 120 than that which holds the lock-bolt in its locking position. The lever N is so balanced that the forked end is heavier than the end carrying the pins $b b'$, by reason whereof the points of the prongs on the dial-arm of the lever will 125 always be caused to fall inside of the path of the pin d . This will effectually prevent the pin from striking directly against the ends of the prongs, as might happen if it were sought to hold the lever in its various adjustments 130 by means of sliding contact produced by a spring pressing against it.

By using two adjusting-pins, as above indicated—one for setting the lever N for a single

holiday, and the other, when the lever is to be adjusted, for two consecutive holidays—there will be less likelihood of making a mistake in adjusting the position of the lever than 5 when these several adjustments are effected by a single pin. The pin b' and its stops in no wise interfere with the use of the pin b in adjusting the lever for a single holiday; and, on the other hand, the position of the 10 stop c' is such that it becomes necessary to make use of the pin b' if the lever is to be set for two consecutive holidays. This stop renders it also practically impossible, when using the pin b for setting the lever N for a single 15 holiday, to carry the lever too far. The stud or stop c , while not absolutely necessary, is of utility so far as it serves to hold the lever in place against such possible accidental misplacement as might occur without it. It might 20 be of special importance if the lever N were evenly balanced on its pivot, or if, being heavier at one end than the other, it should be so frictioned as not to turn readily on the pivot.

In the Chinnock lock, patented as above 25 stated, the lock-bolt, when withdrawn from the locking position against the force of the spring O , is held retracted for the desired period of time by the pivoted detent-lever Y . This operates as follows: When the unlock- 30 ing-pin d , revolved by the dial, strikes the lever N and depresses the main unlocking-lever M , the rounded end of this latter lever strikes the horizontal arm or head z of the detent Y , moves it aside, and passes below it, the 35 detent then moving forward again under the influence of the counter-weight Y' , and engaging with the end of lever M , and holding it in the depressed position against the opposing force of the spring O . A second pin, d' , 40 carried by the dial D , can be made to unlock the lever M from this detent at any desired time, according to the hour for which such pin d' may have been set. This it does by striking against the projection z' . If, however, it 45 be desired at any time to cause the lock to lock up at an hour earlier than that for which the pin d' has been set, the detent Y can be tripped by hand by opening the door A' of the lock-case. In order, also, to do this without 50 opening the door of the lock-case, (which would be inconvenient if the key of such door were kept by a person other than the one having immediate custody of the lock, and which, on general principles, should be avoided as far 55 as possible, in order to prevent accidental derangement of the adjustments of the mechanism,) I have provided a tripping mechanism which can be operated from the exterior of the lock. This is shown in Fig. 5, which 60 shows in plan the parts lying below the dotted line $g\ g$ of Fig. 4. It consists simply of a lever, m , pivoted to the lock-door A' , to one end of which lever there is secured a handle, m' , which projects through a slot in the lock-door, 65 and to the other end of which there is secured a pin, m^2 , which takes in under the weighted end of the detent-lever Y . A spring, m^3 , may

be used to hold the pin m^2 in its lowest position, except when the operator takes hold of the handle m' . When the detent Y is lifted 70 away from the lever M , the spring O will carry the lock-bolt forward to such an extent that the detent will not re-engage with the lever M until this lever is again depressed, as in the act of unlocking. It follows that when the 75 detent Y has been disengaged from the lever M the lock is in condition for "instant locking"—that is, will lock up instantly upon the closing of the safe-door and the throwing of the door-bolts. 80

What is claimed as new is—

1. The combination, in a time-lock, of a lock bolt or dog, a time-movement or clock acting on the same through the medium of a revolving device, and an electromotor connected with said lock bolt or dog independently of such device, and capable of withdrawing the bolt from the locking position with a slow motion, substantially as and for the purpose set forth. 85

2. The combination, in a time-lock, of a lock bolt or dog, a time-movement or clock acting on the same through the medium of a revolving device, and an electromotor connected with said lock bolt or dog, both through 95 the medium of such revolving device and independently thereof, substantially as and for the purpose set forth.

3. The combination, in a time-lock, of a lock bolt or dog, an electromotor for retracting the same from the locking position, and a cut-out for automatically short-circuiting such motor, and thus arresting its action when the bolt is fully retracted. 100

4. The combination, in a time-lock, of a lock bolt or dog, an electromotor for retracting the same from the locking position, and an indicator arranged to be operated by such electromotor, substantially as and for the purpose set forth. 105

5. The combination, in a time-lock, of a revolving device actuated by the time-movement or clock thereof, and an adjustable forked lever arranged to be acted on by said revolving device, said lever being made heavier at one 115 end than the other and loosely pivoted, so as to be brought into the operative position by the force of gravity, substantially as and for the purpose set forth. 110

6. The combination, in a time-lock, of an adjustable forked lever interposed between the dial and the lock-bolt, and two adjusting devices, one of which operates in connection with a fixed stop for regulating the position of such lever when setting the lever for a single day, substantially as and for the purpose 125 set forth.

7. The combination, in a time-lock, of an adjustable forked lever interposed between the dial and the lock-bolt, one or more adjusting devices for regulating the position of such lever, and positive stops to prevent the accidental displacement of the lever, substantially as set forth. 130

8. The combination, in a time-lock, of the bolt-operating lever, an adjustable forked lever pivoted thereto in position to be acted on by the dial, one or more adjusting devices for regulating the position of such forked lever, and inclined stops on the bolt-operating lever for such adjusting devices to operate against, substantially as and for the purpose set forth.
- 5 9. The combination, in a time-lock, of an unlocking-lever, a detent for holding said lever in the retracted position, and an operating-connection passing through the lock-case for tripping such detent from the exterior of the lock-case.
